DESIGN FOR A BRIDGE FOR AN OPHTHALMIC MOUNTING

George E. Nerney, Attleboro, Mass., assignor to
Bay State Optical Company, Attleboro, Mass.,
a corporation of Maine

Application March 26, 1934, Serial No. 51,186

Term of patent 3½ years

To all whom it may concern:

Be it known that I, GEORGE E. NERNEY, a citizen of the United States, and a resident of Attleboro, in the county of Bristol, State of Massachusetts, have invented a new, original, and ornamental Design for a Bridge for an Ophthalmic Mounting, of which the following is a specification, reference being had to the accompanying drawing forming a part hereof.

In the drawing,
Figure 1 is a front elevation of a bridge for

an ophthalmic mounting showing my new design, and

Figure 2 is a top plan view of the bridge for an ophthalmic mounting shown in Figure 1.

I claim:

The ornamental design for a bridge for an ophthalmic mounting substantially as shown.

In witness whereof, I have signed my name to this specification this 20 day of March, 1934.

GEORGE E. NERNEY.
